UNITED STATES PATENT OFFICE.

EDWARD FRANKLIN GROTH AND WILLIAM WALTER JONES, OF BRIDGEPORT,
CONNECTICUT.

DOUBLE SNAP-HOOK.

1,175,437.

Specification of Letters Patent. Patented Mar. 14, 1916.

Application filed June 24, 1915. Serial No. 36,029.

To all whom it may concern:

Be it known that we, EDWARD FRANKLIN GROTH and WILLIAM WALTER JONES, citizens of the United States, residing at Bridgeport, 5 in the county of Fairfield and State of Connecticut, have invented certain new and useful Improvements in Double Snap-Hooks, of which the following is a specification.

The invention relates to improvements to 10 double snap-hooks, designed particularly for use in fastening antiskidding chains upon automobile tires, but which may be used with equal effectiveness for various other purposes, such as upon hitching 15 chains, draft chains, and the like.

The object of the invention is to provide 20 a cheap, simple and efficient double snap-hook, and relates particularly to the novel, and inexpensive and efficient manner of connecting the spring tongue to the hook.

In the drawings, illustrating the invention, in the several figures of which like parts are similarly designated, Figure 1 is 25 a perspective view of our improved snap-hook. Fig. 2 is a side elevation of the same drawn on a larger scale. Fig. 3 is a face view of the same. Fig. 4 is a face view of the spring tongue. Fig. 5 is a side elevation of the link of the hook, the spring being 30 omitted. Fig. 6 is a face view of the same. Fig. 7 is a horizontal section drawn on a larger scale on the line *a—a* of Fig. 2.

1 designates our improved snap-hook, constructed preferably of malleable metal, and 35 comprising an open link having one end 2 thereof cut away, as at 3, to provide a seat 3' for the free end of the spring tongue 4, the opposite end of said spring tongue being held in a saw slot 5 (Fig. 5) produced 40 in the opposite end 2' of the link, the end of the spring tongue being securely held in position in the end 2' of the link in a manner as will now be described.

The sides of the spring tongue 4, adjacent 45 to the anchor end thereof, are formed with notches or recesses 6, the width of the metal of the spring tongue between the notches or recesses being slightly less than that of the diameter of the end 2' of the link or loop, 50 whereby to permit the metal of the link or loop being forced inwardly to securely fasten the spring tongue in position.

In the manufacture of the link, the blank, (as shown in Figs. 5 and 6), is first formed,

the base or notched end of the spring tongue 55 4 is then inserted in the saw slot 5, with the free end of the tongue resting against the seat 3', after which the sides of the end 2' of the link are compressed and bent inwardly as shown at 7, in Figs. 2, 3 and 7, 60 so as to close the sides of the saw slot and force the metal into the notches or recesses 6 of the spring tongue 4, thus securely locking the base end of the latter to the end 2' of the hook, and it will be noted that the 65 seat 3' is located out of vertical alinement with the center of the saw slot 5, so that the free end of the spring tongue 4 will normally be held into engagement with its seat.

In practice, the body portion of the link 70 is bent inwardly toward the spring tongue so as to fit the curvature of an automobile tire when the hook is used for fastening an antiskidding chain thereon.

It will be understood that the sides of the 75 metal may be forced together and into the notches or recesses 6 by placing the loop upon a suitable die-block and striking the opposite side with a hammer, or by means of a suitable stamp-press having suitably 80 shaped die-block and punch for forcing the metal of the link into the notches or recesses as the punching tool descends, as will be readily understood.

It will thus be seen that we provide an 85 exceedingly simple and efficient snap-hook, which can be manufactured at considerably less cost than those now upon the market, and one by which connections between the 90 ends of a chain may be readily made, and, furthermore, by our construction, it will be apparent that, in the event of injury to our snap-hook, a new snap-hook may be readily attached to the chain without necessitating special work, such as would be required with 95 a snap-hook having a loop at one end and a tongue at its opposite end.

What we claim is:—

1. A snap hook comprising an open link provided at one end with a tongue-receiving 100 slot, and a tongue mounted in said slot, the faces of the slot being compressed against the faces of the tongue entirely across the width of the tongue and the lateral margins of the link opposite a portion of the tongue 105 in the slot being engaged against side portions of said tongue.

2. A snap hook comprising an open link

provided at one end with a tongue-receiving slot, and a tongue having one end mounted in the slot, said end being provided with oppositely disposed marginal notches, the material of the link on opposite faces of the tongue when inserted engaging said opposite faces entirely across the width of the tongue and the marginal portions of said material opposite the notches engaging in the notches.

10 In testimony whereof we have hereunto

set our hands this 19th day of June, A. D. 1915.

EDWARD FRANKLIN GROTH.
WILLIAM WALTER JONES.
